FLOOR CLEANING DEVICE

Frank H. Lyons, Memphis, Tenn., and Jacob F. Ferdon, Little Rock, Ark., assignors to E. L. Bruce Co., Memphis, Tenn., a corporation of Delaware

Application April 10, 1947, Serial No. 740,550

13 Claims. (Cl. 15—231)

1

This invention relates to a simple form of floor cleaning device and more particularly to a manually operable floor cleaning device primarily intended for household use, such as is disclosed in our copending application Serial No. 683,606, filed July 15, 1946, and now abandoned, and of which this application is a continuation-in-part. There are on the market today various liquid compositions for cleaning and maintaining linoleum, wood, and other floors; and, the present invention is primarily intended for use with a liquid cleaning composition which includes a wax or waxes suspended in petroleum and/or coal tar solvents and which is non-aqueous in character. Manual application of such cleaning liquids by means of mops, rags, lamb's wool and other similar materials involves much effort and otherwise is not satisfactory. Such materials not only absorb the cleaning agent and soon become matted and caked with dirt and dried wax, but also lack a desirable mild abrasive action sufficient to remove dirty surface films, particularly where polishing compositions containing wax have been applied to the floor.

Accordingly, it is an object of this invention to provide an implement for easy application of cleaning and maintenance compositions to floors, the implement being so organized that it will not become matted and caked with dirt which progressively impairs the effectiveness of a floor cleaning implement.

Another object of this invention is to provide a floor cleaning implement, the working surface of which will not absorb the liquid cleaning composition, but will spread the liquid uniformly over the surface of the floor to be cleaned.

Still another object of the invention is to provide a cleaning device that will furnish a desirable mild abrasive action without scratching or otherwise marring the surface finish of a floor.

Another object of the invention is to provide a floor cleaning implement with a wear element which may be replaced, simply and readily, after it has become excessively worn.

A further object of the invention is to provide a labor-saving, manually-operable floor cleaning implement that can be used easily and comfortably by an operator standing in an erect position, with the expenditure of very little effort.

Other objects and advantages of the invention will become apparent from the following description and accompanying drawings in which:

Figure 1 is a longitudinal cross-sectional view through our floor cleaning implement assembled, ready for use upon a floor.

2

Figure 2 is a perspective view of the replaceable element of the implement.

Figure 3 is a perspective view of the permanent part of the implement.

5 Figure 4 is a plan view of the underside of the permanent part of the implement, with the replaceable element removed.

Figure 5 is a sectional view taken on a line corresponding to 5—5 of Figure 1 of another embodiment of the permanent portion of the implement.

10 Figure 6 is a side view of the replaceable portion of the implement, folded for packaging and shipment.

15 Referring now to the drawings, it will be seen that the floor cleaning implement of this invention comprises two main parts namely, a replaceable steel wool pad assembly, indicated generally at 1, and a handled rigid backing member, indicated generally at 2. Although the shape of the pad 1 and backing member 2 is shown rectangular, the shape is not critical. Preferably, however, the pad and backing member have a longer dimension in one direction than in the other.

25 Thus, a generally preferred shape may be described as oblong.

The undersurface of the backing member 2 is provided with outwardly projecting flexible fibers, indicated generally at 3 in Figures 1 and 5, which engage the pad 1. It has been found that the combination of a layer of steel wool 4, backed by flexible fibers 3 arranged generally normal thereto, possesses desirable characteristics for a floor cleaning implement for use with many of the available liquid floor cleaning compositions. The steel wool not only provides a mild abrasive action that is necessary to loosen thoroughly the surface dirt, but being non-absorbent of the cleaning composition used, does not become matted with dirt and other foreign matter in use. Furthermore, the steel wool serves effectively to spread the cleaning liquid uniformly over the surface of the floor. The fibers 3 of the backing member 2 provide a cushioned backing for the

40 steel wool 4 sufficiently resilient to preclude its marring the finish of the floor, while at the same time permitting the wool to reach and clean all surface depressions or uneven spots that may be found on a floor. In addition, the fibers 3, when 45 the implement is used, engage, and to some extent penetrate, the steel wool 4 to aid in holding the latter in working position on the backing member 2 without relative slipping or sliding. This engagement and penetration also acts to 50 prevent the steel wool from separating and roll-

ing up in use. In this way, a substantially uniform thickness of the layer of steel wool 4 is maintained until it becomes so thin, by wear, that replacement is necessary.

The fibers 3 of the backing member 2 may be provided in several ways, two of which are shown in the drawings. As shown in Figures 1 and 4, the undersurface of the backing member 2 is covered with pile carpeting in which the base fabric 5 preferably is provided with spaced areas of pile arranged to form generally parallel rows of tufts 6 with intermediate clearance spaces 7. The carpeting preferably is of the cut pile type, but it has been found that uncut pile carpeting also gives satisfactory results. The carpeting is cemented, stapled, or otherwise suitably secured to the undersurface of the backing member 2 with the rows of tufts 6 extending transversely thereof. As an example of dimensions which give satisfactory results, the base fabric 5 of the carpeting when uncompressed by use may be about $\frac{1}{8}$ inch thick and the pile tufts 6 about $\frac{1}{8}$ inch long. The rows of tufts 6, form a definitely ribbed surface, with, for example, about five ridges to the inch. These dimensions are, of course, given as examples and are susceptible to variation and change, but it has been found that pile carpeting with these approximate specifications possesses the desirable steel wool cushioning and engaging characteristics for the floor cleaning implement. The ribbed surface is preferred to a flat surface so that dirt and other foreign matter that may come into contact with the carpeting may accumulate in the spaces 7 from where it easily may be dislodged. Furthermore, the ribbed surface provides a somewhat more resilient or cushioning backing than a flat surface. The back of the carpeting preferably is treated with a sizing, such as a resinous composition which is insoluble in the presence of the floor cleaning composition and serves to prevent unravelling or deterioration of the carpet in use.

The fibers 3 also may be provided by making the backing member 2 in the form of a conventional scrubbing brush, having regularly arranged tufts 8 of fiber bristles set in a wood back, as shown in Figure 5. The bristles should be of a length to prevent their flattening out in use, and to provide some rigidity at the ends which are in contact and engagement with the steel wool 4. The length of the bristles also should be such as to maintain sufficient resiliency for a proper cushioning backing for the steel wool. We have found that about one-half inch in length is preferable for ordinary bristles, this length being about one-half the length of bristles of a conventional scrubbing brush. The longer bristle length, as compared to the pile tufts, is necessary because bristle fibers usually are much stiffer than pile fibers, and the bristles must be long enough to provide sufficient flexibility for a cushioned backing. But the bristle length may be varied somewhat depending on the fineness of the bristles, which should be fine enough to engage and penetrate the steel wool 4 so as to frictionally retain the pad 1 in working position on the backing member 2 without relative slipping or sliding.

The top of the backing member 2 is provided with a handle 9 of sufficient length to enable the operator, while using it, to stand erect. The handle may be attached to the backing member by a connecting member 10 provided with a handle-receiving socket 11 and oppositely dis-

posed transversely extending pivot pins 12. Bearing brackets 13 are fastened to the backing member 2, as by screws, and pivotally receive the pins 12, to secure the handle to the backing member for pivotal movement in a plane substantially normal thereto. The handle 9 may be fastened in the socket 11 by any conventional means, such as by friction, cement, or a bolt or screw 14, as shown, extending through aligned holes in the handle and the sides of the socket. It will be noted that the pivotal connection shown is sufficiently low to permit the handle to be brought almost in line with the plane of the backing member for reaching beneath low pieces of furniture and the like. From this construction, it will be apparent that the implement is intended to be used with a reciprocating motion. This back and forth action over the surface of the floor is of substantial importance in the use of the implement, as will be explained later.

The replaceable pad assembly 1 (see Figure 2) preferably is substantially the same as that disclosed in the copending application of C. Arthur Bruce and Frank H. Lyons, filed August 26, 1946, Serial No. 693,144, now U. S. Patent No. 2,497,206. The pad assembly 1 comprises a generally rectangular pad or mat of one or more layers of metallic wool 4 having binding or attaching means secured to the ends thereof. The wool 4 may be reinforced against separating or rolling up in use by one or more rows of stitching 15 extending transversely of the pad intermediate the ends thereof. The end binding means may be tabs 16 of relatively stiff sheet material which is folded over the ends of the wool pad and suitably secured thereto. Staples 17, as shown, are found to be practical. The ends of the wool pad also may be stiffened suitably by the application of fluid plastics such as synthetic resins which can be set by application of heat and pressure to consolidate the ends of the pad. The tabs 16 or stiffened end portions of the wool pad serve to assemble initially the pad in working position on the backing member, as will be described later.

The metallic wool 4 preferably is steel wool of No. 00 to No. 1 grade, or a mixture of several such grades. Steel wool is particularly effective when used with cleaning compositions of the wax and petroleum and/or coal tar solvents type. But it will be understood, however, that for use with aqueous cleaning liquids, any non-rusting metallic wool having properties similar to those of steel wool may be used. The metallic wool pad preferably has two or more layers therein, in each of which the filaments are arranged generally or substantially in parallelism, as the result of a combing or like process. All the filaments are not exactly parallel, but extend generally in the same direction. Expressed in another manner, the pad may be said to have a grain. Commercial steel wool, purchased in rolls, usually has such a filamentary arrangement. The filaments of the working layer of the pad, i. e. the bottom layer if more than one layer is used, preferably extend generally at an angle of about 17° to the longitudinal centerline of the pad. It will be understood that the filaments are, therefore, at an angle to the direction of travel of the pad when in use, with the consequent benefits described in the aforementioned application Serial No. 693,144. This angle may be anywhere from 0° to about 30° and still obtain desirable results from the use of the pad. An angle of 0° prolongs

the life of the pad but, while effective, does not provide as much abrasive action as a larger angle. An angle of 30°, on the other hand, while providing increased abrasive action, nearly reaches the point where this action becomes excessive, with consequent marring of the floor finish. A 30° angle also nearly reaches the point where the filaments will unduly tear, separate, or roll up upon encountering a rough spot or obstruction on the surface of the floor. Therefore, an angle of about 17° is preferred, but it will be understood that any angle between 0° and 30° may be used, since the filaments will then lie generally or substantially parallel to the direction of travel of the implement when in use.

When the pad has two or more layers of filaments, the filaments in one layer preferably lie at an angle to the filaments in the other layer, as described in the aforementioned application Serial No. 693,144, so that the cushioning backing fibers 3, in penetrating the layers of metallic filaments to some extent, will tend to interlock the filaments against fraying in use.

Surrounding the periphery of the backing member 2 is a collar-like binding strip 18 of material such as carpet, webbing, rubber or other elastic material, synthetic resin, etc. The strip 18 preferably is treated with sizing or like material which will prevent deterioration in the presence of the liquid cleaning compositions used, or the binding strip should be of material which will resist deterioration without such treatment. We have found "Koroseal", a synthetic material (plasticized polyvinyl chloride) produced by the Goodyear Rubber Company, to be quite suitable. The binding should be stiff enough to retain the tabs 16 of the pad in place as later described, but soft enough to provide a bumper cushion which prevents marring of furniture upon accidental contact of the implement therewith. As shown in the drawings, the binding strip has several peripheral ridges formed thereon, which both reinforce the strip and add to the bumper cushion effect described above. The binding strip 18 is approximately as wide as the thickness of the backing member 2 and is secured to the longitudinal side faces thereof by tacks, glue, staples, or any other suitable means. Staples 19 are shown in the drawings as the securing means. The binding strip 18, prior to attachment to the backing member 2 is drawn tightly across the end faces thereof for a purpose later described. If the binding strip is formed of a relatively inelastic or non-stretchable material, it is desirable that some looseness be provided in the lower edges of those portions thereof which lie across the flat end faces of the backing member. The purpose of this looseness is described later. One method of obtaining this looseness is to provide a lower offset 20 (see Figure 5) on the longitudinal side faces of the backing member 2. Equivalent methods of obtaining the desired looseness readily will be apparent. For the purpose intended, the binding strip 18 need not surround the entire periphery of the backing member 2, but may consist of separate strips of material stretched across each end face of the backing member and secured to the opposite longitudinal side faces thereof. A binding surrounding the entire periphery is preferred, however, to provide a bumper cushion, as previously described.

The pad 1 is assembled on the backing member 2 by inserting the tabs 16 into the spaces between the end faces of the backing member and the binding strip 18. The looseness of the lower por-

tion of the strip, where it crosses the end faces of the backing member, both facilitates this insertion and allows space enough for the reception of the tabs 16, but at the same time the strip, particularly at the upper portions thereof, is tight enough to retain frictionally the tabs in place.

This engagement of the tabs 16 serves to position, initially, the pad 1 on the backing member 2, the fibers 3, of which, frictionally engage the steel wool 4. The tabs 16 are somewhat wedge-shaped in cross-section because of the bulk of the steel wool 4 projecting along one edge from between the double walls thereof. This wedge or V-shape of the tabs 16, aids materially in inserting and holding the tabs in place under the binding strip 18.

Still another feature of the replaceable pad assembly is that it is quite flexible and readily may be rolled up or folded, as shown in Figure 6, into a very small space and so conveniently packaged for sale as replacement articles.

In use, a quantity of liquid cleaning material is applied to an area of the floor and the implement is pushed back and forth over the surface of the area to be cleaned. The steel wool spreads the cleaning material evenly over the surface to be cleaned, and, at the same time, gently abrades and loosens the surface dirt and other foreign matter. Very little pressure of the implement on the floor is required other than the weight of the implement itself, except in spots relatively more soiled than the remaining area of the floor, thus making for ease of operation. Because the steel wool is substantially self-cleaning in the presence of the solvent component of the cleaning material, upon completion of the spreading and simultaneous cleaning operation, there usually will remain on the floor a thin film of cleaning material plus the loosened dirt. This easily may be removed by placing a cloth rag or other suitable waste on the floor and rubbing the rag over the surface with the implement. This subsequent operation does not aim to dry the floor completely, but to leave it with some of the cleaner composition thereon, in order to obtain the benefit of the wax content of the cleaning composition. By employing this method, it has been found that no "rings" or marked borders appear between overlapping cleaned areas.

While the implement has been described as being of marked value in the manual cleaning of floors, the implement also has been found to have superior characteristics in the application of floor seals, waxes, and other non-aqueous finishing and maintenance products to floors.

It will be realized that we have described a specific embodiment of our invention, but that we do not wish to be unduly limited thereby. Therefore, our invention embraces all modifications and embodiments as fall within the spirit and scope of the appended claims.

We claim:

1. A floor cleaning implement, the combination comprising; a backing member having a substantially flat undersurface, an operating handle pivotally secured to said member for movement in a plane normal to said surface, and a metallic wool pad detachably secured to said backing member and overlying said undersurface, said pad having at least one working layer of wool the filaments of which are in substantially straight parallel arrangement and extend in a direction generally parallel to said flat undersurface and lie at an angle of from 0° to about 30° to the plane of the pivotal movement of said handle.

2. A floor cleaning implement, the combination comprising; a rigid backing member having a substantially flat undersurface, resilient fibers secured to said member and projecting outwardly from said undersurface, an operating handle pivotally secured to said member for movement in a plane normal to said surface, and a metallic wool pad detachably secured to said backing member in overlying engagement with said fibers, said pad having at least one working layer of wool the filaments of which are in generally straight parallel arrangement and extend in a direction substantially parallel to said undersurface and lie at an angle of from 0° to about 30° to the plane of the pivotal movement of said handle.

3. A floor cleaning implement as set forth in claim 2 in which the fibers comprise the pile of carpeting secured to the undersurface of the backing member.

4. A floor cleaning implement as set forth in claim 2 in which the backing member and cushioning fibers are in the form of a bristle brush.

5. A floor cleaning implement, the combination comprising; a rigid backing member having a substantially flat undersurface, cut pile carpeting secured to said surface with the pile projecting outwardly therefrom, an operating handle pivotally secured to said member for movement in a plane normal to said surface, and a metallic wool pad detachably secured to said backing member in overlying engagement with said carpeting, said pad having at least one working layer of wool the filaments of which are arranged generally in parallelism and extend in an angular direction of from 0° to about 30° to the plane of the pivotal movement of said handle.

6. A floor cleaning implement as set forth in claim 5 in which the pile of the carpeting is arranged in spaced, substantially parallel rows forming a series of spaced tufted ribs extending transversely of the filaments of the working layer of wool of the pad.

7. The structure set forth in claim 11 in which the pad binding means comprises folded tabs with the said edges of the pad secured within the folds of the tabs.

8. A floor cleaning implement, the combination comprising; an oblong, substantially flat rigid backing member, flexible cushioning fibers secured to said member and projecting outwardly from the undersurface thereof, an operating handle pivotally secured to said backing member for movement in a longitudinally disposed plane normal to said member, each of the opposite end faces of said member having strip means of relatively flexible material extending transversely thereacross and secured to said member, and an oblong metallic wool pad detachably secured to said member in overlying engagement with the ends of said fibers, said pad having at least one working layer of wool the filaments of which are arranged generally in parallelism and extend in an angular direction of from 0° to about 30° to the longitudinal axis of said backing member, and binding means stiffening the opposite ends of said pad, said ends being adapted to be inserted between said strip means and said end faces to secure detachably said pad on said member.

9. A floor cleaning implement, the combination comprising; a rigid backing member, means secured to said member providing a substantially flat, rough, cushioning surface on the underside

10 thereof, an operating handle pivotally secured to said member for movement in a plane normal to said surface, and a metallic wool pad detachably secured to said backing member in overlying engagement with said surface, said pad having at least one working layer of wool, the filaments of which are in substantially straight parallel arrangement and lie in planes generally parallel to said flat surface, the directional orientation of said filaments relative to the plane of the pivotal movement of said handle being an angle of from 0° to about 30°.

15 11. A floor cleaning implement, the combination comprising: a generally rectangular, rigid backing member having a substantially flat undersurface; an operating handle pivotally secured to said member for movement relative thereto in a plane substantially normal to two opposite edges thereof; and a generally rectangular, metallic wool pad overlying said undersurface, the two 20 opposite marginal edge portions of said pad adjacent said opposite edges of said backing member being detachably secured to said member and said pad having at least one working layer of 25 wool the filaments of which are in substantially straight parallel arrangement, lie in planes generally parallel to said undersurface, and extend in an angular direction of from about 60° to 90° to said opposite edges of said member.

30 12. A floor cleaning implement, the combination comprising: a generally rectangular, rigid backing member having a substantially flat undersurface; an operating handle pivotally secured to said member for movement relative thereto in a plane substantially normal to two 35 opposite edges thereof; means defining slots associated with said member adjacent and parallel to and extending substantially the length of said opposite edges; a generally rectangular, metallic wool pad overlying said undersurface, said pad having at least one working layer of wool the filaments of which are in substantially straight parallel arrangement, lie in planes generally parallel to said undersurface, and extend 40 in an angular direction of from about 60° to 90° to said opposite member edges; and binding means stiffening the two opposite edge portions of said pad adjacent said opposite member edges, said stiffened pad edge portions being adapted 45 to be inserted in said slots to detachably secure said pad to said backing member.

50 13. A floor cleaning implement, the combination comprising: a generally rectangular, rigid backing member having a substantially flat undersurface; an operating handle pivotally secured to said member for movement relative thereto in a plane substantially normal to two opposite peripheral faces thereof; strip means 55 of flexible material overlying the length of each of said faces and secured to said member; a generally rectangular, metallic wool pad overlying said undersurface, said pad having at least one working layer of wool the filaments of which are in substantially straight parallel arrangement, lie in planes generally parallel to said undersurface, and are directionally oriented at an angle of from 0° to about 30° to the plane of movement of said handle; binding means stiffening the two opposite edge portions of said pad adjacent said opposite peripheral faces, said stiffened pad edge portions being adapted to be inserted between said strip means and said opposite peripheral faces to detachably secure said pad on said backing member.

55 14. In a floor cleaning implement assembly

the combination of a generally rectangular, rigid backing member having a substantially flat undersurface and a handle pivotally secured thereto for movement in a plane substantially normal to two opposite edges thereof; a generally rectangular, substantially flat pad of metallic wool having at least one working layer of wool the filaments of which are in substantially straight parallel arrangement, lie in planes substantially parallel to the plane of the pad, and extend in 10 an angular direction of from about 60° to 90° to two opposite edges of said pad; and means for detachably securing said pad to said backing member to overlie said undersurface thereof with said opposite pad edges disposed substantially 15 parallel to said opposite edges of said member.
